United States Patent Office

Des. 215,908
Patented Nov. 4, 1969

215,908

COMBINED BILLFOLD AND PURSE

Murray Wolf, 849 Niles Road, Union, N.J. 07083

Filed Jan. 21, 1969, Ser. No. 15,418

Term of patent 14 years

Int. Cl. D3—02

U.S. Cl. D87—3

FIG. 1

FIG. 2

FIG. 1 is an outer side view of a combined billfold and purse, in unfolded condition, showing my new design;

FIG. 2 is an inner side view thereof;

FIG. 3 is an edge view thereof; and

FIG. 4 is perspective thereof in folded condition.

I claim:

The ornamental design for a combined billfold and purse, substantially as shown.
